(57) CLAIM

The ornamental design for a bowl with lid as shown and described.

DESCRIPTION

FIG. 1 is a front, top and left side perspective view of a bowl with lid, showing my new design;

FIG. 2 is a rear, bottom and right side perspective view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a front elevational view thereof; and,

FIG. 8 is a rear elevational view thereof.

The broken lines in the figures illustrate the portions of the bowl with lid and form no part of the claimed design.

The dot-dash broken lines immediately adjacent to the claimed areas in the views represent the boundaries of the design and form no part thereof.
